CLAIM

The ornamental design for a display screen with animated graphical user interface, as shown and described.

DESCRIPTION

FIG. 1 is an image in a sequence of a first embodiment of a display screen with animated graphical user interface showing our new design;

FIG. 2 is another image of the first embodiment;

FIG. 3 is another image of the first embodiment;

FIG. 4 is another image of the first embodiment;

FIG. 5 is another image of the first embodiment;

FIG. 6 is an image in a sequence of a second embodiment of a display screen with animated graphical user interface;

FIG. 7 is another image of the second embodiment;

FIG. 8 is another image of the second embodiment;

FIG. 9 is another image of the second embodiment; and,

FIG. 10 is another image of the second embodiment.

The appearance of the graphical user interface of the display screen transitions sequentially between the images shown in FIGS. 1-5. The appearance of the graphical user interface of the display screen transitions sequentially between the images shown in FIGS. 6-10. The process or period in which one image transitions to another image forms no part of the claimed design. The broken lines in the drawings depict the display screen and associated graphics of the graphical user interface and form no part of the claimed design.

1 Claim, 10 Drawing Sheets
